[57] CLAIM

The ornamental design for ribbed brake pad for a roller skate, as shown and described.

DESCRIPTION

FIG. 1 is a perspective view of a ribbed brake pad for a roller skate showing our design;

FIG. 2 is a side elevational view of the pad shown in FIG. 1, the side opposite being a mirror image;

FIG. 3 is a top plan view of the pad shown in FIG. 1; FIG. 4 is a rear elevational view of the pad shown in FIG. 1;

FIG. 5 is a front elevational view of the pad shown in FIG. 1; and,

FIG. 6 is a bottom plan view of the pad shown in FIG. 1.
